Original application Feb. 5, 1962, Ser. No. 171,321, now
Patent No. 3,144,726. Divided and this application
June 9, 1964, Ser. No. 382,679

2 Claims. (Cl. 40—78)

(Granted under Title 35, U.S. Code (1952), sec. 266)

This is a division of application Serial No. 171,321, filed
February 5, 1962, now Patent No. 3,144,726.

The invention described herein may be manufactured
and used by or for the Government for governmental
purposes without the payment of any royalty thereon.

The present invention relates to a mechanism for pro-
ducing an illusion of motion from a succession or series
of picture-bearing cards, film or the like, by manipulation
thereof in such a manner that successive cards or film of a
series thereof may be removed from one portion of a stack
or supply thereof and deposited at another position within
such stack or supply in a manner so that, after viewing,
each card will come to assume its original serial position
as the stack or supply thereof becomes exhausted by such
manipulative operations. These operations can be car-
ried out at such speed that there appears to the eye of a
viewer an illusion of continuous or uninterrupted motion
between the pictures or images on successive cards or at a
slower speed enabling reading or close viewing of individ-
ual cards. Viewing of the individual cards successively
is accomplished as each is held stationary momentarily
at one point in the above cycle.

Accordingly, an object of the present invention is to
provide a mechanism of the above-indicated character
which is useful as a training aid in connection with mili-
tary training, but which is also adaptable to a wide diver-
sity of applications.

A second object of this invention is to provide for an
inexpensive viewer of opaque film frames, which is manu-
ally operated, and compact and simple in construction and
operation, which is readily adapted to motor driven opera-
tion and a multitude of uses involving the manipulation
of various types of intelligence bearing or intelligence re-
ceptive sheets.

The structural features of an embodiment of the invention
are illustrated in the accompanying drawings, in
which:

FIG. 1 is a perspective view, partly in section of the
embodiment;

FIG. 2 is a vertical section taken on the line 2—2 of
FIG. 1;

FIG. 3 is a fragmentary sectional view showing a por-
tion of the construction of FIG. 2, and showing operation
of the card-manipulating means;

FIG. 4 is a vertical section of the embodiment shown
in FIG. 1, taken on the line 4—4 of FIG. 2;

FIG. 5 is a horizontal sectional view taken on line 5—5
of FIG. 2;

FIG. 6 is a view similar to FIG. 3 but showing a differ-
ent operating position of the parts including the card-
manipulating means.

It will be understood that the term "cards" as used
throughout the present description is intended to include
in addition to flexible opaque image bearing cards, trans-

2

parent and translucent image bearing photographic film
which is to be manipulated in like manner to opaque cards
in the construction illustrated in the accompanying draw-
ings.

FIGS. 1—6 show an embodiment of this invention which
contains a single chamber cylinder encased magazine for
use with opaque motion picture cards. The embodiment
comprises an external case 120 within which is mounted
cylinder 123 on axle 122 turned by crank 121. Within
the cylinder 123 is magazine 126 loaded with rectangular
shaped opaque motion picture cards 127. Attached to
the interior of external case 120 are tabs 125 which, start-
ing at one point of the circular motion of the cylinder,
project through the wall of the cylinder through slots 124
to make contact with the uppermost picture card 127 in
magazine 126. As tab 125 makes contact with the upper-
most picture, the picture card itself is withdrawn from
the magazine 126 and the magazine continues to rotate
while the picture card remains stationary. In this position
the picture card 127 can be seen through the viewing
aperture 129 as the cylinder rotates in a 180° arc.

FIG. 3 shows tabs 125 making initial contact with the
uppermost picture card. FIG. 2 shows the picture card
127 remaining in position as the cylinder and magazine
continue to rotate. FIG. 6 shows the picture card as it
begins the re-entry process into the magazine. This re-
entry is assisted by inwardly directed projection 130 which
forces the card to assume a position in parallel with the
other cards in the magazine. It will be noted that there
is a channel 128 between the inner surface of the sleeve
which comprises the outer circumference of the cylinder
and the filling material 131 surrounding the magazine on
one side only. This channel 128 enables the card 127
to remain stationary at the viewing aperture 129 only for
a 180° turn of the cylinder, as the channel does not extend
beyond the point of re-entry into the magazine. After the
first picture card completes its cycle the cylinder will turn
to another 180° before tabs 125 again cause the uppermost
picture to be removed from the magazine. As the cylin-
der is turned rapidly the cards replacing one another in
the viewing aperture will create the illusion of movement.

I claim:

1. A device for viewing in succession a series of indicia-
bearing cards, said device comprising:

a. a rotatable cylinder, said cylinder being transparent
throughout a portion of its circumference;

b. a frame encasing and mounting said cylinder, said
frame having a viewing area through which said cyl-
inder can be seen;

c. a card-holding magazine encased within said cylinder
and rotatable therewith, said magazine having a card
entry portal and a card exit portal, a portion of the
outer side of said magazine being spaced from the
inner side of said cylinder along the distance from
the exit portal to the entry portal to permit passage
of an indicia-bearing card from the exit to entry
portal;

d. means for rotating said cylinder and magazine;

e. card withdrawal and holding means comprising an
internally projecting card contact tab fastened to said
frame and extending through a slot in said cylinder

- for contacting said card at said exit portal as the magazine rotates under the tab, said tab holding the outermost card in the magazine in a stationary viewing position until the card entry portal of the rotating magazine becomes aligned with said stationary card; and
- f. card deposit means comprising a card guide positioned on said cylinder over the entry portal to force the tab-held card into the rotating magazine entry portal as the portal becomes aligned with the card.
2. The viewing device of claim 1, wherein said cylinder is transparent throughout the area from the exit portal of

said magazine to the entry portal, wherein said card guide comprises an indentation in said cylinder over the forward edge of the magazine entry portal and wherein said card contact tab comprises a strap of spring metal.
